Primary Examiner — Amanda Christensen

(57) **CLAIM**

The ornamental design for a portable power bank as shown and described.

DESCRIPTION

FIG. 1 is a front perspective view of a portable power bank showing my new design;

FIG. 2 is a rear perspective thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a rear perspective view of thereof shown in a used condition.

The broken lines in the Figures are for the purpose of illustrating portions of the portable power bank that form no part of the claimed design.
